(57) **CLAIM**

The ornamental design for a tool caddy, as shown and described.

DESCRIPTION

FIG. 1 is a top, right side, front perspective view of a first embodiment of the tool caddy showing our new design; FIG. 2 is a top plan view of the tool caddy of FIG. 1; FIG. 3 is a front elevational view of the tool caddy of FIGS. 1 and 2;

FIG. 4 is a rear elevational view of the tool caddy of FIGS. 1-3;

FIG. 5 is a right side elevational view of the tool caddy of FIGS. 1-4;

FIG. 6 is a left side elevational view of the tool caddy of FIGS. 1-5;

FIG. 7 is a bottom plan view of the tool caddy of FIGS. 1-6;

FIG. 8 is a top, right side, front perspective view of a second embodiment of the tool caddy showing our new design;

FIG. 9 is a top plan view of the tool caddy of FIG. 8;

FIG. 10 is a front elevational view of the tool caddy of FIGS. 8 and 9;

FIG. 11 is a rear elevational view of the tool caddy of FIGS. 8-10;

FIG. 12 is a right side elevational view of the tool caddy of FIGS. 8-11;

FIG. 13 is a left side elevational view of the tool caddy of FIGS. 8-12; and,

FIG. 14 is a bottom plan view of the tool caddy of FIGS. 8-13.

(Continued)

The broken lines show portions of the tool caddy that form no part of the claimed design.

1 Claim, 14 Drawing Sheets
